UNITED STATES PATENT OFFICE.

ELIAS J. HALE, OF FOXCROFT, MAINE.

IMPROVEMENT IN SASH-FASTENERS.

Specification forming part of Letters Patent No. **178,292**, dated June 6, 1876; application filed April 24, 1876.

To all whom it may concern:

Be it known that I, ELIAS J. HALE, of Foxcroft, of the county of Piscataquis and State of Maine, have invented a new and useful Improvement in Sash-Fastenings; and do hereby declare the same to be fully described in the following specification and represented in the accompanying drawings, of which—

Figure 1 is a sectional elevation, and Fig. 2 a transverse section; of a window-frame and its two sashes with my improved fastening applied thereto. Fig. 3 is a side view of the bolt, and Fig. 4 a perspective view of the bolt-actuator.

In carrying out my invention I use a perforated bolt, applied to a window-frame, as described, in combination with an actuating-spring, provided with an arm, and applied to said bolt and frame, as hereinafter more fully described and definitely claimed.

In the drawings, A denotes the window-frame, and B and C its sashes, the lower of the said sashes being movable vertically within such frame.

There is inserted in a hole, *h*, made horizontally in the frame, a slide-bolt, D, both being arranged with the lower sash in manner as shown. Such sash has a series of notches or bolt-receiving holes, *a a*, made in it, to open out of that vertical edge of it which is next to the bolt.

The bolt has a perforation or hole, *b*, bored in it at or near its middle, such hole being to receive a stud, *c*, projecting from and making part of the actuator E, which consists of a wire bent in manner as shown in Fig. 4, the part *d* of it constituting what may be termed the "arm," and the part *e* being the spring. This latter is to be fastened at or near its lower end to the window-frame, in which there is to be formed a chamber, *f*, to admit of the play or movement of the spring, all being arranged and applied substantially as represented.

The bolt may be inserted in the sash, and the actuator be applied directly to the latter and the bolt, in which case the frame should have a series of notches or recesses to receive the bolt, in order for the sash to be supported by it at different heights in the frame. It is preferable, however, to have the bolt and the actuator applied directly to the frame, as herein first explained.

By pressing the thumb against the arm of the actuator the said actuator may be moved so as to force back the bolt out of engagement with the sash. On the thumb being removed from the arm the spring of the actuator will cause the bolt to be thrown forward into engagement with the sash when at any proper height to receive the bolt.

I usually construct the bolt of wood; but it may be of metal or other suitable material.

The actuator, being composed of a single piece of wire, can be made very cheaply, and is of easy application to the frame.

I claim—

1. As an improved article of manufacture, the perforated bolt D, in combination with the single piece of wire E, bent as represented, so as to form a combined spring, *e*, arm *d*, and stud *c*, and applied to such bolt, as set forth, the two being arranged with the sash and its supporting-frame, essentially as specified.

2. The frame A, provided with the bolt-receiving hole *h*, the actuator-receiving chamber *f*, the perforated bolt D, and the wire E, bent as represented, so as to form a combined spring, *e*, arm *d*, and stud *c*, all being arranged and applied substantially as set forth.

ELIAS J. HALE.
